[57] **CLAIM**

The ornamental design for a holder for a fountain pen and ink cartridges, as shown and described.

DESCRIPTION

FIG. 1 is a perspective view taken from the top front end of the holder for a fountain pen and ink cartridges according to the present invention;

FIG. 2 is a perspective view taken from the top and rear of the holder according to the present invention;

FIG. 3 is a rear elevational view of the holder according to the present invention;

FIG. 4 is an elevational view of the left side of the holder of FIG. 3;

FIG. 5 is an elevational view of the right side of the holder of FIG. 3;

FIG. 6 is an elevational view of the front of the holder of FIG. 1;

FIG. 7 is a top plan view of the holder of FIG. 1; and, FIG. 8 is a bottom plan view of the holder of FIG. 1.

The fountain pen depicted by means of broken lines in FIGS. 1 through 7 has been shown for illustrative purposes only and form no part of the claimed design.
